UNITED STATES PATENT OFFICE

HERBERT E. TAUTZ, OF MILWAUKEE, WISCONSIN, ASSIGNOR TO DELTA MANUFACTURING COMPANY, OF MILWAUKEE, WISCONSIN, A CORPORATION OF WISCONSIN

PLANER ATTACHMENT FOR JOINTERS

Application filed April 15, 1929. Serial No. 355,231.

This invention has for its object to provide an attachment for jointers which will permit the work of a planer being done thereon.

Another object of the invention is to accomplish this purpose by providing a detachable frame carrying an adjustable upper plate parallel with the table and against which the work that has had one face dressed may be caused to bear while having a parallel face dressed.

Another object of the invention is to provide such an attachment with means for holding the work against the upper plate while being fed to the cutter.

Another object of the invention is to simplify the construction and render it inexpensive to manufacture and suitable for small size machines such as used in the so-called "home workshops".

With the above and other objects in view the invention consists in the planer attachment for jointers as herein claimed and all equivalents.

Referring to the accompanying drawings, in which like characters of reference indicate the same parts in different views,

Fig. 1 is a front view of a jointer suitable for receiving the planer attachment forming the present invention;

Fig. 2 is an end view thereof;

Fig. 3 is a view similar to Fig. 1 with the planer attachment substituted for parts of the jointer;

Fig. 4 is a central vertical sectional view through the attachment on the plane of line 4-4 of Fig. 5;

Fig. 5 is an elevation partly in section of the attachment as seen from the right of Fig. 4, and

Fig. 6 is a sectional plan view on the plane of line 6-6 of Fig. 5.

In these drawings, 10 indicates a base having a cutter arbor 11 mounted in suitable bearings therein and driven by any suitable power connected by a belt (not shown) with the grooved pulley 12 on the end thereof. A front table 13 and a rear table 14 are slidably mounted on inclined ways 15 so as to be raised or lowered with respect to the knives as usual, an adjusting nut 16 being threaded on

an adjusting screw 17 and engaging a bracket on the table for sliding it in the ways and a removable screw 18 being threaded in the table and projecting through a slot in the ways and carrying a spring 19 for clamping the table to the ways, though permitting of the sliding movement for adjustment. The tables are thus independently adjustable. The front table is provided with a fence or work guide adjustable laterally across the table and also angularly with respect to the table. For this purpose a bracket 20 is slidable in ways across the bottom of the table and is provided with a clamping screw 21 for holding it in its adjustments, while a supporting plate 22 is pivotally mounted thereon by having an arc-shaped groove 23 on its vertical face fitting on a corresponding arc-shaped rib in the vertical face of the bracket, there being a clamping screw 24 on the bracket extending through an arc-shaped slot 25 in the supporting plate for clamping it in its angular adjustments. A hollow guide member 26 is carried by the mounting plate 22 as a gauge or guide for the work to bear against in its travel past the cutters. A set screw 27 threaded in a lug of the bracket and engaging a lug on the mounting plate serves as a convenient means for quickly obtaining the usual normal position of the fence with respect to the table.

The machine as described constitutes a jointer capable of dressing a face on a piece of work accurate with respect to an adjacent face but unsuitable for producing true, straight and smooth surfacing in a plane parallel with the plane of the dressed face. Such work is usually done on large planing machines having top and bottom cutters for dressing both faces at the same time, but the present invention provides an attachment for the jointer adapting it to guide the work from above and thereby cut a surface true, straight and smooth and parallel with respect to the guided surface.

Such attachment comprises a frame 28 having an inclined bottom fitting on the ways 15 after removing the front table 13. Such frame is clamped to the ways by the screw 104

18 and spring 19 in the same manner as the table. Vertical guides are formed in the frame 28 by means of rods 29 accurately fitted in the top and bottom walls thereof and a carrier 30 is adjustably slidable on said vertical rods 29 and is raised or lowered by a jack-screw 31 threaded centrally therein with a thrust bearing in the top of the frame and a crank handle 32 for turning it.

10 The carrier 30 has vertical parallel V grooves on one side of its ends to receive the rods 29 as an open bearing, while a clamping rod 33 passes loosely through an opening in the conical central part of the carrier and bears at its ends on the vertical rods 29 opposite said open bearings and a set screw 34 threaded through the central portion of the carrier engages said clamping rod 33 and forces it into clamping engagement with the rods 29 to rigidly and firmly hold the carrier in a definite relation to the frame and consequently a definite relation with the cutter.

15 A guide plate 35 is attached by screws 36 to the bottom of the carrier 30 and is accurately fitted to have its bottom surface serve as a guide for the work parallel to the table and the cutter in all positions of the carrier.

20 For holding the work against the guide plate 35 and for advancing the work to the cutter there is provided a swinging presser feed roll 37 turned by a hand crank 38. A pin 39 extends across the frame from one side to the other and has pivotally mounted on it a U-shaped member 40 carrying a shaft 41 in its extended arms, which shaft is turned by the crank handle 38 on its end and carries the pressure and feed roller 37, preferably formed in sections of fluted rubber and positioned between the arms of member 40.

25 Attached to the swinging feeding and pressure roller frame by fitting on the pin 39 and shaft 41 therewith is an arm 42, to which a spring 43 is attached, said spring having other connection with any suitable support permitting it to exert a pull on the arm that will swing the member 40 to lift the roller 37, the opening in the frame through which the shaft 41 passes being considerably larger than such shaft to permit of such lifting movement.

30 In operation the gauge plate 35 is adjusted to a height above the knives according to the required thickness for the work, conveniently measured from the top of the rear table. Then the work is entered between it and the feed roll 37 with its previously dressed face in contact with the gauge plate and is fed to the cutter by the turning of the crank 38, the spring 43 swinging the feed roll to keep it in driving engagement with the work and compensate for unevenness thereof. In the travel of the work between the cutter and the top plate or gauge its bottom face will be finished true, straight and smooth and parallel with its top face at the proper distance

therefrom. If two adjacent edges are faced on the jointer in the usual way the other two faces may be readily cut by the use of this attachment, permitting work to be done at home comparing favorably with the work of full size machines at the planing mill.

35 The inexpensive machine suitable for home use may be quickly converted from a jointer to a planer by applying this attachment and the only adjustment necessary is the positioning of the gauge plate, which is quickly and easily accomplished.

What I claim as new and desire to secure by Letters Patent is:

1. The combination with a jointer having a base, a cutter thereon, inclined guides formed on the base, and tables adjustably mounted on the guides adapting the cutter to dress one face of the work; and an attachment replacing one of the tables to adapt the cutter to dress the opposite face of the work relative to the first mentioned face comprising a frame detachably mounted on the inclined ways in place of the table, a gage plate carried thereby at a distance above the cutter, and means on the frame for holding the work against the gage plate as it passes over the cutter.

2. The combination with a jointer having a base, a cutter thereon, inclined guides formed on the base, and tables adjustably mounted on the guides adapting the cutter to dress one face of the work; and an attachment replacing one of the tables to adapt the cutter to dress the opposite face of the work relative to the first mentioned face comprising a frame detachably mounted on the inclined ways in place of the table, a gage plate carried thereby at a distance above the cutter, and means on the frame for holding the work against the gage plate and feeding it to the cutter.

3. The combination with a jointer having a base, a cutter thereon, inclined guides formed on the base, and tables adjustably mounted on the guides adapting the cutter to dress one face of the work; and an attachment replacing one of the tables to adapt the cutter to dress the opposite face of the work relative to the first mentioned face comprising a frame detachably mounted on the inclined ways in place of the table, a gage plate carried thereby and adjustable with respect to its distance above the cutter, and means on the frame for holding the work against the gage plate and feeding it toward the cutter.

4. A woodworking machine comprising a jointer having a table and a cutter beneath the table, the front end of the table being detachably and adjustably mounted on inclined ways, a frame adapted to be mounted on such ways in place of the table end, a gauge plate adjustably mounted in the frame to different positions above the cutter, and a suitably operated swinging feed roll mounted in the

frame to hold work against the gauge plate and advance it toward the cutter.

5. A planer attachment for jointers comprising a frame having means adapting it to be detachably secured to the jointer table ways, an adjustably mounted top gauge plate thereon, and a swinging feed roll on the frame for holding the work against the gauge plate and advancing it.

10 6. A planer attachment for jointers comprising a frame adapted to be detachably secured to the jointer table ways, vertical guide rods therein, a carrier slidably mounted on the guide rods, a jack-screw for raising and lowering the carrier, a top gauge plate carried by the carrier, and means for holding work against the top gauge plate.

7. A planer attachment for jointers comprising a frame adapted to be secured to a jointer, a pair of vertical guide rods therein, a carrier having grooves fitting against the guide rods, a clamping bar passing through an opening in the carrier and bearing on the guide rods, a screw threaded in the carrier and engaging the clamping bar for clamping it against the guide rods, a top gauge plate carried by the carrier, and means for pressing work against the gauge plate.

8. A planer attachment for jointers comprising a frame adapted to be detachably secured to the jointer table ways, an adjustable top gauge plate carried thereby, a pin extending across the frame, a U-shaped member pivotally mounted on the pin, a shaft passing through the arms of the U-shaped member, a feed roll on said shaft between the arms, means for turning the shaft, and means for swinging the U-shaped member for causing the feed roll to press work against the gauge plate.

40 9. A planer attachment for jointers comprising a frame adapted to be detachably secured to the jointer table ways, a vertically adjustable top gauge plate thereon, a pin passing through the frame, a U-shaped member pivotally mounted thereon, a shaft carried by the arms of the U-shaped member, a feed roller on the shaft between said arms, a crank handle on the shaft for turning the feed roller, an arm projecting from the U-shaped member, and a spring connected therewith for swinging the U-shaped member to cause the feed roller to press work against the gauge plate.

55 In testimony whereof I affix my signature.
HERBERT E. TAUTZ.
